UNITED STATES PATENT OFFICE.

PHILIP WILL AND FREDERICK WILL, OF ROCHESTER, NEW YORK, ASSIGNEES TO SILL STOVE WORKS, OF ROCHESTER, NEW YORK, A CORPORATION OF NEW YORK.

COMBINATION-STOVE.

1,307,388.

Specification of Letters Patent. Patented June 24, 1919.

Application filed June 3, 1915. Serial No. 31,986.

To all whom it may concern:

Be it known that we, PHILIP WILL and FREDERICK WILL, citizens of the United States, residing at Rochester, in the county 5 of Monroe, State of New York, have invented a certain new and useful Improvement in Combination-Stoves, of which the following is a specification, reference being had therein to the accompanying drawings.

10 This invention relates to stoves but more particularly to such as are adapted to use both solid and fluid fuel.

One of the principal objects of this invention is to provide a stove which is exceedingly compact and which is so constructed and arranged as to obtain a very high efficiency. Further objects of the invention are to provide a structure which is capable of being used with either solid or 20 fluid fuel or both simultaneously, and a system of damper control which makes accidents practically impossible.

The many other features and advantages of the invention will be fully understood 25 from the following description and included in the claim.

One embodiment of the invention is shown in the drawings in which:—

Figure 1 is a front elevation of the invention with portions of the stove casing removed, the oven dampers being in their open position, as will be fully described hereinafter.

Fig. 2 is a section on line 2—2 of Fig. 1, 35 the parts being in the same position as in that figure.

Referring to the drawings, the stove casing 10 is mounted on a base or support 11. Within this casing is the usual solid fuel 40 fire box 12 to which is connected the outlet flue 13, best shown in Fig. 1 of the drawings. This flue 13 passes downwardly beneath the partition 14 above which are the fluid burners 15 of any desired pattern. 45 These top burners 15 are in the substantially inclosed chamber 16 here formed by the partition 14, the stove top 17 and the upright walls 18. Air for these burners 15 preferably enters the chamber 16 through 50 one or more openings 19 about the burner pipes which are preferably of sufficient size for the purpose. Exit damper 20 controlled by the arm 21 connects this chamber 16 with the usual rear flue 22. The usual top openings 23 of the stove are preferably provided 55

with solid covers 24 such as are commonly used on solid fuel stoves.

The flue 13 is here provided with a damper outlet 25 directly connecting the same with the rear flue 22 though this may be omitted if desired. The side wall 26 of the fire box preferably extends upwardly to a point above the normal level of the top 27 of the oven, and the end portion 27a of this top preferably turns upwardly and connects with the upper portion of this side wall, as shown in Fig. 1 of the drawings. With this construction the heated gases from the fire box are deflected downwardly by the end 29 of the partition 14 in the direction indicated by the arrow, pass laterally into the downward flue 30, thence into the flue 31 beneath the oven, and then through the vent 32 into the rear or chimney flue 22. A division flue plate 33 between 70 the oven bottom and the main bottom of the stove preferably projects forwardly within this flue chamber 31 from the rear wall 34 sufficiently to cause the heat to pass forwardly under the oven and then turn 80 rearwardly toward the vent 32 previously described. Thus it will be seen that in the present embodiment the heat is generated in the fire box 12 on one side of the oven, passes over the top, down the opposite side, 85 then beneath the same and upwardly on the rear side thereof, thus subjecting this oven to heat on five of its six sides.

By so constructing the stove that the heated gases are deflected downwardly by 90 the partition 14, this partition becomes heated to a high temperature which radiates into the chamber 16, and this high temperature is well maintained therein for there is little opportunity for the escape of 95 the heat therefrom, as this chamber is substantially inclosed. Thus the covers 24 over the chamber 16 are subjected to this heat and cooking may be readily done thereon when a solid fuel fire is maintained. 100

By the deflecting downwardly of the heated gases by the casing 14, such gases are projected against the oven top and a more intense heat is produced in such oven than would be the case if these gases 105 merely moved horizontally thereover upon leaving the fire box, as is generally the case. By utilizing the space 35 as a portion of the oven, extra radiating surface is obtained.

Beneath the top 27 is the oven 28 which is adapted to be heated by the combustion of solid fuel in the fire box in the manner described. In the flue 31 is a partition 36 which, with the front wall 37 of the stove and the oven bottom 38, forms a chamber 39 within which is mounted the fluid burner 40 of any desired type. This chamber 39 communicates with the oven 28 by means 10 of the long vent or port 41 which is controlled by the damper 42 hinged at its edge 43 and operated by the rod 44.

Within the oven is preferably placed a deflector plate 45 here mounted on slides 46 to permit the same to be readily withdrawn therefrom. In the front portion of the flue 15 13 is a partition 47 which with the top wall 27 of the oven and the front wall 37 of the stove forms a flue chamber 48. Along the 20 front portion of the top oven plate 27 beneath this chamber 48 are a plurality of vents 49 connecting this chamber with the oven and at one end of the chamber 48 is a port 50 preferably in the under wall there- 25 of communicating with the flue 30. This port 50 is here controlled by a centrally mounted revoluble damper 51. By connecting the chamber 48 with the flue 30 in this way, there is no possibility of the products 30 of combustion from the fire box entering the port 50 when both forms of fuel are being used simultaneously, for this port opens in the same direction that these products are traveling. This is a distinct advantage over 35 earlier constructions in which the axis of the port has been generally at a right angle to the direction of travel of the products of combustion.

After leaving the chamber 48, the products 40 of combustion of the fluid fuel burner pass through the flues 30, 31 and 22 in the order named as did the products of combustion from the fire box and thus the oven is heated directly and indirectly thereby. 45 With the arrangement of the deflector plate and the chamber 48 shown in the drawings, the heated gases from the burner 39 first

pass rearwardly beneath the deflector plate, and then upwardly and forwardly to practically the front of the oven where they enter the chamber 48, and thus the entire oven is uniformly heated. While this has been found to be an advantageous arrangement, any other might be substituted therefor if preferred. 50

On account of the limited space which is available for stoves in modern houses and apartments, it is particularly important that the parts be consolidated as much as possible so that a considerable amount of cooking may be done on a small stove. By moving the top burner box inwardly over the oven in the manner shown in the drawings and previously described, there are always available for immediate use six top openings 60 for solid fuel cooking and four when fluid fuel is used in a size of stove in which there are but six top openings altogether. Also when the fluid fuel top burners are being used alone, sufficient heat is generated in the top burner box to produce an excellent warming action on the top of the stove directly over the solid fuel fire box, due to radiation from the partition 14. 65 70

What we claim as our invention and desire to secure by Letters Patent is:— 75

In a device of the class described, a casing, a fire box for the consumption of solid fuel, an oven beside said fire box, a top burner box over said oven but with its under wall 80 spaced therefrom, said burner box extending substantially to said fire box and having substantially its entire under wall directly exposed to the heated gases from said fire box, and one or more fluid fuel burners in said 85 burner box.

In testimony whereof we affix our signatures in the presence of two witnesses.

PHILIP WILL.
FREDERICK WILL.
